UNITED STATES PATENT OFFICE.

JOHN MINOR BOTTS LEWIS, OF LYNCHBURG, VIRGINIA, ASSIGNOR TO COWMATIC CORPORATION, OF LYNCHBURG, VIRGINIA, A CORPORATION OF VIRGINIA.

COW-STALL.

1,379,769.

Specification of Letters Patent. Patented May 31, 1921.

Application filed May 20, 1920. Serial No. 382,967.

To all whom it may concern:

Be it known that I, JOHN M. B. LEWIS, a citizen of the United States, residing at Lynchburg, in the county of Campbell and State of Virginia, have invented certain new and useful Improvements in Cow-Stalls, of which the following is a specification.

This invention relates to cow stalls, and more particularly to stalls formed by an overhead horizontal stall rail and a plurality of vertical rods secured to the horizontal rail and dividing the stall space into separate stalls in which stanchions are arranged.

15 In the care of live stock, it is the present practice to employ stanchions supported on an overhead horizontal stall rail, the individual stalls being formed by vertical rods arranged between each pair of stanchions 20 in substantially the same vertical plane with the stanchions and a partition rod being secured to the vertical posts.

In the prior art, the use of a single post stall has been disclosed, but this construction is open to the objection that it provides a considerable space between the anchored arm of the stanchion and the stall post, and a cow oftentimes gets her head into the space. Under such conditions, it is difficult 30 to get the cow to enter the stanchion.

It has also been proposed to employ a stall post construction consisting of an upper vertical post terminating a considerable distance above the floor and a pair of spaced 35 lower posts connected to the upper position by inclined sections. Such construction prevents the cow from placing her head in the space between the anchored arm of the stanchion and the stall post, and at the same 40 time permits free movement in the upper portion of the space which is advantageous.

One of the disadvantages of the construction above described is that a cow entering the stall may insert her head between the 45 stall post and the anchored arm in the space above the end of the upper stall post and when she lowers her head, as she naturally does to eat, the inclined portions of the lower spaced stall post forming a wedge 50 shaped opening with the anchored arm and the cow wedges her head in the lower contracted space between the anchored stanchion arm and the lower spaced post. To withdraw the cow's head, it is necessary

that she raise it to the upper portion of the 55 stall and step backward, but as a general rule, the cow will attempt to withdraw by stepping backward without raising her head, resulting in injury.

In the present invention, I have provided 60 a construction wherein the connecting portions between the upper stall post and the lower spaced posts is substantially horizontal and prohibits or prevents the cow from inserting her head in the manner set 65 forth between the stall post and the anchored stanchion arm. The present construction has all of the advantages of the stall posts of the prior art, consisting of a single upper section and spaced lower sections; in that it prevents the cow from entering the space between the stall post and the anchored stanchion arm, as frequently 70 happens when a single stall post is employed, and also provides plenty of space 75 in the upper portion of the stall to permit free movement of the head of the cow when she has entered the stanchion.

In the accompanying drawings, I have shown one embodiment of the invention. In 80 this showing,

Figure 1 is a perspective view of a portion of several adjacent stalls showing a stanchion in dotted lines, and

Fig. 2 is a detail sectional view of one 85 of the stall posts.

Referring to the drawings, the reference numeral 1 designates the horizontal supporting rail which is best arranged in the same vertical plane with the curb 2 of the stalls. 90 A number of stanchions may be arranged on the horizontal rail. As shown in dotted lines, the stanchion 3 is supported from the rail as at 4, and is anchored in suitable securing means 5 arranged in the curb. As 95 shown, stall posts are arranged on each side of the stanchion.

The improved stall post forming the subject matter of the present invention comprises an upper vertical section 6 which is 100 secured to the horizontal rail in any suitable manner and a horizontal connecting section 7 secured to the lower end of the vertical section. Spaced lower posts 8 are arranged at each end of the horizontal section and anchored in the curb or floor. As shown, the members 6, 7, and 8 are arranged 105 in the same vertical plane with the hori-

zontal rail and the curb of the stall. A partition member 9 is secured to the vertical post 6, and as shown, it may be secured at the junction of the vertical post and the 5 horizontal connecting member.

In Fig. 2 of the drawings, I have shown in detail one manner of connecting the various parts of the stall posts. As shown, the lower posts and the horizontal connecting 10 member are secured to each other by L-shaped members 10 provided with reduced extensions adapted to enter the ends of the members 7 and 8, reduced ends 11 being provided with openings 12 for the passage of 15 a pin or other securing means. A similar member 12 having four reduced sections 14 is adapted to be secured in the lower end of the vertical post, the two extensions arranged opposite each other entering the 20 horizontal connecting member and the fourth reduced portion entering the partition 9. Openings 15 may be provided for fastening elements.

By reference to Fig. 1 of the drawings, it 25 will be readily seen that the present invention provides a construction of stall posts which prevents a cow from inserting her head between the stall posts and the anchored arm of the stanchion. It also prevents the cow from placing her head between the anchored arm of the stanchion and the stall post above the lower spaced sections of the post and moving her head downwardly so as to catch her neck in the 30 restricted space between the lower stall post section and the anchored arm. At the same time, when the cow is properly positioned with her head in the stanchion, plenty of 35 room is provided for free movement.

40 It is to be understood that while I have described the preferred embodiment of my invention, various changes in shape, size, and arrangement of parts may be resorted to without departing from the spirit of the 45 invention or the scope of the subjoined claims.

Having described my invention, what I claim is:

1. In cow stalls, the combination with a horizontal supporting rail and stanchions 50 supported thereon, of an upright member connected to the supporting rail and extending downwardly, a horizontal member secured to said upright member at a point below the normal level of a cow's neck, and 55 spaced vertical members secured to each end of said horizontal member and secured to the floor.

2. In cow stalls, the combination with a horizontal supporting rail and stanchions 60 supported thereon, of an upright member connected to the top rail and extending downwardly, a horizontal member secured to said upright member at a point below the normal level of a cow's neck, spaced vertical 65 members secured to each end of said horizontal member, and a partition secured to said upright member and to said horizontal connecting member.

3. In cow stalls, the combination with a 70 stall curb and a horizontal supporting rail arranged in substantially the same vertical plane with the curb, said horizontal supporting rail being adapted to support a plurality of stanchions, of an upright member 75 connected to the supporting rail, said upright member terminating at a point above the floor and below the level of a cow's neck, a horizontal member secured to the lower end of said upright member, and 80 spaced vertical members secured to each end of said horizontal member and to the floor, said members being arranged in substantially the same vertical plane with the horizontal supporting rail and the curb. 85

In testimony whereof I affix my signature in presence of two witnesses.

JOHN MINOR BOTTS LEWIS.
